UNITED STATES PATENT OFFICE.

JOHN A. CANFIELD, OF DANBURY, CONNECTICUT.

COIN-ADDING MACHINE.

1,389,122.

Specification of Letters Patent. Patented Aug. 30, 1921.

Application filed June 24, 1920. Serial No. 391,295.

To all whom it may concern:

Be it known that I, JOHN A. CANFIELD, a citizen of the United States, residing at the city of Danbury, in the county of Fairfield and State of Connecticut, have invented 5 certain new and useful Improvements in Coin-Adding Machines; and I do declare the following to be a full, clear, and exact description of the invention, such as 10 will enable others skilled in the art to which it appertains to make and use the same.

This invention relates to certain new and useful improvements in a coin register especially designed for small savings banks, 15 and it has for its principal object to provide a simply constructed mechanism of the coin-connector type wherein the coin receiver and holder is moved from its receiving position to its depositing position and during such movement or actuation the 20 registry or adding mechanism is coupled therewith by the coin for variable degrees of movement determined by the denomination 25 of the coin.

Further, the invention resides in the novel features of construction and the arrangements and combinations of parts hereinafter described and claimed, reference 30 being made to the accompanying drawing wherein—

Figure 1 is a front elevation of a coin register embodying the present invention the casing being broken away to show more 35 clearly the inclosed mechanism;

Fig. 2 is a vertical transverse section thereof taken about on line 2—2 of Fig. 1; and

Fig. 3 is a detailed horizontal sectional 40 view through the coin chute on line 3—3 of Fig. 1.

The improved register may be superposed on a bank or receptacle (not shown) or the coin can be deposited on the base 45 1 of the casing 2 which provides for a coin chamber in its lower part.

A shaft 3 is journaled in the sides of the casing and loose on this shaft are the dollars drum 4, the tens drum 5 and the units 50 drum 6, the tens drum receiving the units drum with a tight frictional fit whereby movement of the latter will impart corresponding movement to the tens drum. From Fig. 1 it will be observed that the 55 outer drum 5 has its peripheral wall, which

surrounds the inner, units drum, uniformly notched, and through these notches 7 are read the numerals on the periphery of drum 6, which in this instance are "5". The wall portions of drum 5, opposite the notches or 60 cut-outs, bear numerals which are designed to be read in conjunction with those on drum 6, while the projections 8 bear complete numerals and are designed to conceal or cover the inner drum at the sight opening of the casing.

The dollars drum may be coupled in any suitable manner with the drum 5 so as to register every complete revolution thereof. The tens drum, by reason of its frictional, 70 telescopic relation with the units drum, rotates freely therewith in a progressive manner but retrograde movement of drum 5 is prevented by a spring pawl 9 upstanding from the base 1 and engaging in a series of 75 holes or depressions 10 about the periphery of said drum 5. Consequently, oscillation of the inner drum will impart only progressive motion to the outer drum in an intermittent manner.

Fixed on the shaft 3 adjacent the units drum is a coin chute 11 having an expandible section 12 pivoted thereto at its lower end and yieldably urged into contracted relation therewith by a spring 13 interposed 80 on the shaft between said section and the fixed manipulating lever 14. The inner end of the chute lies parallel with the outer side face of the inner drum and is provided with transverse slots or openings 15 through 90 which coupler pins 16, fixed on the drum, may readily pass except when obstructed by a deposited coin 17. The chute is formed so as to arrest a coin of predetermined value opposite the respective slot 15, and the arrested coin will then, upon movement of the handle 14 and chute 11, engage the corresponding drum pin 16 to carry the drum along therewith for a predetermined movement. At the end of this movement the 100 coin will be released by opening or expanding movement of the chute section 12. To effect this release movement, the upper end of said section is formed with a right angular, cam projection 18 which is adapted to 105 ride on a fixed abutment 19 upstanding from the base and shift the chute section away from the chute and against the compression of the coiled spring 13. The coin thus released will slide out through the in-

verted upper end of the chute into the coin chamber below. The handle is then raised or retracted and in so doing brings the chute against a stop pin 20 on the inner 5 drum which returns the latter to normal position while the outer drum is retained in its newly advanced position by the spring pawl 9.

While the registering device can be constructed for registering all denominations of coins from one cent upward, the embodiment here depicted is designed for registering only three denominations, namely nickels, dimes and quarters. The lowermost 15 slot in the chute is covered by the dime, the uppermost by the quarter, and the intermediate by the nickel. In operation, when one of the three coins named is placed in the chute and the shaft rotated, the coin 20 will block its slot 15 and strike against its corresponding coupler pin or peg to thereby revolve the inner drum and simultaneously revolve the outer drum, owing to the frictional engagement therebetween. 25 The spring pawl is inclined on the under side so as to readily yield and permit concurrent rotation of the drums. The downward movement of the handle is continued until the cam member on the chute engages 30 and rides on the abutment which will spread the chute members and release the coin to drop into the bank.

Now, with the lever forced down to its limit and the coin discharged, the pawl 9 35 will just be leaving one of the notches 10, but on the return or upward movement of the lever this pawl will instantly reengage in the notches as soon as the chute has abutted against the stop pin 20. Continued return 40 of the lever to its normal position will cause this pin 20 to revolve the inner drum independently against its frictional resistance, the outer drum meanwhile being held back by the spring pawl.

45 The chute, for registering a nickel, will, of course, have a greater arc of free movement than for coins of higher denominations. The coin is resiliently grasped by the expandible chute and is also secured therein 50 by the coupling pin. The construction is exceedingly simple and accurate in operation, the size of the coin determining the degree of movement of the drums which is a positive movement controlled throughout by 55 the coin coupling. Obviously, the casing will have a coin-insert slot as shown, beneath which the chute normally returns and is disposed.

What is claimed is:

60 1. A coin register comprising a shaft, an inner drum loose thereon, an outer drum also loose thereon and frictionally receiving the first drum whereby the two drums will rotate as a unit, said drums bearing monetary 65 values on their peripheries and the outer

drum having peripheral series of recesses, a pawl coöperating with the recesses to hold the outer drum against retrograde action, and means on the inner drum for selective engagement to rotate the same. 70

2. A coin register comprising a shaft, an inner drum loose thereon, an outer drum also loose thereon and frictionally receiving the first drum whereby the two drums will rotate as a unit, said drums bearing monetary 75 values on their peripheries and the outer drum having peripheral series of recesses, a pawl coöperating with the recesses to hold the outer drum against retrograde action, a coin chute mounted on the shaft alongside 80 the adjacent side face of the inner drum and provided with a plurality of transverse edge slots, and coupler pins fixed on the side face of the inner drum each in an arc including a slot of the chute whereby the empty slot 85 may pass over the respective pin.

3. A coin register comprising a shaft, an inner drum loose thereon, an outer drum also loose thereon and frictionally receiving the first drum whereby the two drums 90 will rotate as a unit, said drums bearing monetary values on their peripheries and the outer drum having peripheral series of recesses, a pawl coöperating with the recesses to hold the outer drum against retro- 95 grade action, a coin chute mounted on the shaft alongside the adjacent side face of the inner drum and provided with a plurality of transverse edge slots, a coupler pin fixed on the side face of the inner drum for each 100 chute slot for passing therethrough and adapted to be coupled to the chute by a coin blocking the respective slot, and means for effecting release of a coin from the chute.

4. In a coin register, a shaft, drums there- 105 on bearing monetary values, a coin chute composed of two members pivoted together at one end and formed to receive a coin in their opposite ends, means to mount said members on the shaft, spring means for nor- 110 mally urging the two members together, means to coin-couple the chute to the drums, and means for moving the members apart to release the coin and to allow same to gravitate out of the said opposite ends of the 115 members upon the members reaching a pre-determined position.

5. In a coin register, a shaft, drums there- 120 on bearing monetary values, a coin chute composed of two channeled members piv- 125 oted together at one end and having their channels confronting each other and connected to the shaft between their ends, a cam on one member, a fixed abutment for engagement with the cam to move the mem- bers apart and thereby release the coin, means to coin-couple the chute to the drums, and a coil spring on the shaft engaged with one of the members to urge same toward the other member. 130

6. In a coin register, a shaft, drums thereon bearing monetary values, a coin chute composed of a pair of members formed to receive a coin therebetween, means to connect the members to allow of relative movement therebetween, means to mount the chute on the shaft, means to coin-couple the

chute to the drums, and means to move the members relatively apart to thereby release the coin therefrom, upon the chute reaching 10 a predetermined position.

In testimony whereof I affix my signature.

JOHN A. CANFIELD.
